[57] CLAIM

The ornamental design for a paper/napkin holder, as shown and described.

DESCRIPTION

FIG. 1 is a right side, top and front perspective view of a paper/napkin holder showing our new design;

FIG. 2 is a left side elevational view thereof, the right side elevational view being a mirror image;

FIG. 3 is a rear elevational view thereof;

FIG. 4 is a top plan view thereof;

FIG. 5 is a bottom plan view thereof; and,

FIG. 6 is a front elevational view thereof.
